P.C.(57) **CLAIM**

The ornamental design for a bracket, as shown and described.

DESCRIPTION

FIG. 1 is a perspective view of a bracket;

FIG. 2 is a front side view thereof;

FIG. 3 is a back side view thereof;

FIG. 4 is a right side view thereof;

FIG. 5 is a left side view thereof; and,

FIG. 6 is a top view thereof.

The portions of the figures that are presented in broken lines merely illustrate the environment of the design and are not part of the claimed design.
